UNITED STATES PATENT OFFICE.

IRVING HILL, OF WALLACE, CALIFORNIA.

ALPHABETICAL SYMBOLS.

1,021,189.

Specification of Letters Patent. Patented Mar. 26, 1912.

Application filed November 18, 1909. Serial No. 528,656.

To all whom it may concern:

Be it known that I, IRVING HILL, a citizen of the United States, residing at Wallace, in the county of Calaveras, State of California, 5 have invented certain new and useful Improvements in Alphabetical Symbols; and I do declare the following to be a full, clear, and exact description of the same, such as will enable others skilled in the art to which 10 it appertains to make and use the same, reference being had to the accompanying drawings, and to the characters of reference marked thereon, which form a part of this application.

15 This invention relates to improvements in alphabetical symbols for code cipher purposes, the object of the present invention being to produce symbols for the letters of the alphabet in which each and every character 20 will be drawn from a common base and which can be readily traced from such base, also to produce symbols for an alphabet having a separate designation for each sound, such designations being traceable from said 25 common base. Also symbols for an alphabet in which all the signs and marks and symbols are likewise taken from a common base, the whole scheme of the invention being to have a systematic and uniform means 30 for producing symbols representing letters and all of which are taken from a common and standard basic designation whereby each and every symbol for each letter can be readily traced and deduced from said common base. These objects I accomplish by 35 such structure and relative arrangement of lines as will fully appear by a perusal of the following specification and claim.

In the drawings similar characters of reference indicate corresponding parts in the several views.

Figure 1 is a plan of the basic structure used for taking the symbols of the alphabet showing the designating points by numbers. 45 Fig. 2 is a similar view showing the designating points lined to show the symbolic letter structure hereinafter set forth. Figs. 3, 4 and 5 show symbols for letters deduced from the common base shown in Figs. 1 50 and 2 all which will be described herein-after.

As shown in Fig. 1 the base of my improved symbols for an alphabet consists in a square plate having a plurality of indicating points as shown by the numerals on 55 said Fig. 1. In Fig. 2 these several points

are lined through showing the manner of tracing and deducting each letter from such common base. In drawing the symbols for the alphabet from this line base, of course 60 any arrangement could be adopted, but after one had been chosen, it should thereafter be made standard to avoid confusion. As will be seen innumerable designations can be drawn from this common base, and in the 65 specification following I will merely give an example of each class of letter so as to illustrate the matter, but I do not desire to be understood as limiting myself to such. Fig. 3 gives in large size a few of the designations obtainable with the points from which 70 they are deduced shown by corresponding numerals. These numerals, however, would not be used in general practice, but merely for study purposes.

75 In the general scheme for the symbols of the alphabet the square is taken as the common and universal designation, and the point lines drawn thereon. Thus the first letter shown in Fig. 3 the same is taken on 80 the line 3—11 and designates "e" as in "met", "men" and "sell". The second one is taken on the lines 3—11 and 15—17 and designates "e" as in "her", "herd" and 85 "fern", and so on for any designations desired.

Fig. 4 shows designations for all the vowels and the different sounds of each vowel. Thus the first one is taken on the line 15—7 and designates "a" as in "fate", "aid" and 90 "lace" and so on the remaining ones designate the remaining vowels and sounds for each, each one being deducible from the common base.

Fig. 5 shows the consonants drawn from 95 the common base for example, the first one being on line 1—9 and standing for "b".

From the foregoing description it will be readily seen that by taking the common base shown in Figs. 1 and 2, any set of designations for alphabetical letters desired can be drawn and used for any cipher purposes desired. If words are to be symbolized, I would simply set the letter symbols side by side to spell the word.

100 While this specification sets forth in detail the present and preferred construction of the device, still in practice such deviations from such detail may be resorted to as do not form a departure from the spirit of the 110 invention.

Having thus described my invention what

I claim as new and useful and desire to secure by Letters Patent is;

A designating basic form for making symbols for numerals or letters, comprising a square divided into a plurality of points and lines projected to all alined points, as described.

In testimony whereof I affix my signature in presence of two witnesses.

IRVING HILL.
